No. 15,494

Oct. 28, 1884

UNITED STATES PATENT OFFICE

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 15,494, dated October 28, 1884.

Application filed August 7, 1884. Term of patent 3½ years.

To all whom it may concern:

Be it known that I, JOHN QUINCY REED, of the city, county, and State of New York, have invented and produced a new and original 5 Design for a Pattern of a Lady's Walking-Skirt, (numbered 9,354;) and I do hereby declare that the engraved prints accompanying this specification convey to any one accustomed to using paper patterns a clear understanding 10 of how a garment made up by the pattern will appear.

The design shows a round walking-skirt, a deep-pointed right-front drapery displaying draping plaits in its front and back edges, a 15 plain left-front drapery that descends nearly to the bottom of the skirt and appears to over-

lap the front edge of the right-front drapery quite broadly at the top, a deep full back drapery displaying draping plaits in its front edges, loopings at the center, and an outline 20 rounding downward from the right-side edge to a deep point at the left-side edge.

What I claim as my invention, and desire to secure by Letters Patent, is—

The design for a lady's walking-skirt, as 25 shown in the engraved prints accompanying this specification.

JOHN QUINCY REED.
